United States Patent Office

Des. 189,689
Patented Jan. 31, 1961

189,689

LACE FABRIC

David Nussbaum, Brooklyn, N.Y., assignor to D. Strauss
Co., Inc., New York, N.Y., a corporation of New York

Filed Oct. 12, 1960, Ser. No. 62,457

Term of patent 7 years

(Cl. D47—6)

The figure is a plan view of a lace fabric showing my new design.

I claim:

The ornamental design for a lace fabric, substantially as shown.
